UNITED STATES PATENT OFFICE.

EDMUND A. INSKEEP, OF CHICAGO, ILLINOIS.

DESIGN FOR A NOSE-GUARD FOR EYEGLASSES.

SPECIFICATION forming part of Design No. 34,921, dated August 18, 1901.

Application filed July 3, 1901. Serial No. 67,040. Term of patent 7 years.

To all whom it may concern:

Be it known that I, EDMUND A. INSKEEP, a citizen of the United States, residing at Chicago, in the county of Cook and State of Illinois, have invented and produced a new and original Design for a Nose-Guard for Eye-glasses; and I do hereby declare the following to be a full, clear, and exact description of the same, reference being had to the accompanying drawings, forming a part thereof.

This invention relates to a new and original design for a nose-guard for eyeglasses, and is illustrated in the accompanying drawings, in which—

Figure 1 is a plan view of the nose-guard, and Fig. 2 is a side or edge view thereof. Fig. 3 is a rear view of the nose-guard.

The guard consists of a straight flat bar 6 of greater width than thickness. At each end and the middle of this bar laterally-extending circular enlargements 6^a are produced, to each of which is secured a disk 7 of greater diameter. The faces of the disks are finely ridged, as plainly shown in Fig. 1. From one

edge of the bar 6, at its middle enlargement, 25 projects a flat arm 8, which curves laterally toward one end of the bar and also slightly downwardly or away from the plane of the face of the guard. The arm terminates in the squared portion 8^a, which has a perforation 9. 30

The essential features of the design are a bar having three circular enlargements, one at each end and one in the middle, a disk upon each enlargement, and a laterally-projecting arm on one side of the bar. 35

Having thus described my invention, what I claim as new, and desire to secure by Letters Patent, is—

The design for a nose-guard for eyeglasses, 40 as herein shown and described.

In testimony whereof I affix my signature in presence of two witnesses.

EDMUND A. INSKEEP.
